UNITED STATES PATENT OFFICE.

CHARLIE N. CLARK, OF MINNEAPOLIS, MINNESOTA,
Inventor.
Improvement in Furniture-foot and Support. A
Furniture-foot and Support. A
Floor-engaging Furniture-support.

1,159,570.

Specification of Letters Patent.

Patented Nov. 9, 1915.

Application filed February 19, 1912. Serial No. 678,698.

To all whom it may concern:

Be it known that I, CHARLIE N. CLARK, a citizen of the United States, residing at Minneapolis, in the county of Hennepin and State of Minnesota, have invented certain new and useful Improvements in Floor-Engaging Furniture-Supports; and I do hereby declare the following to be a full, clear, and exact description of the invention, such 10 as will enable others skilled in the art to which it appertains to make and use the same.

My invention has for its object to provide a simple and efficient supporting foot or device for bedsteads, dressers, and various other articles of furniture, such as are usually supported on caster wheels, and to such ends, generally stated, the invention consists of the novel construction and arrangement of parts hereinafter described and defined in the claim.

Casters, as is well known, when engaged with the floor, scratch or mar the same by making depressions in the floor. Various 25 substitutes for casters have also been provided and in some instances, the casters have been set in so-called caster sockets. The devices used as substitutes for casters or for the reception of the casters have sometimes 30 been provided with pliable faces and sometimes with hard smooth faces, such as metal or glass, for engagement with the floor. The glass or metal faces, it has been found, will mar or scratch the floors and the pliable 35 faces hitherto employed, have been subject to the objection that they would absorb moisture, and when damp, would stick to the floor or mar the floor finish.

The improved facing which I employ in 40 accordance with my invention is made of pliable material which will not mar the floor and is treated with a water proofing material such as paraffin or other wax, for example, which renders the said pliable facing nonabsorbent of moisture. A pliable nonabsorbing facing of this kind will not stick to a floor and will not scratch or otherwise mar the floor or its finish. This improved facing, in some instances, is applied 45 to a furniture foot to be used as a substitute for a caster, and in other instances, I apply the same to a caster socket for use in connection with a caster. Both of the above kinds of devices I herein designate broadly 50 as a floor engaging furniture support.

My invention also involves novel features

directed to the construction of the furniture foot itself.

In the accompanying drawings which illustrate the invention, like characters indicate like parts throughout the several views.

Referring to the drawings, Figure 1 is a view in side elevation showing the improved furniture foot; Fig. 2 is a vertical section taken on the line $x^2 x^2$ on Fig. 1; Fig. 3 is 65 a view in elevation showing a caster socket provided with my improved facing; and Fig. 4 is a section taken on the line $x^4 x^4$ on Fig. 3.

Referring first to the construction illustrated in Figs. 1, and 2, the numeral 1 indicates a truncated approximately conical metal shell which is spun or pressed from quite thin but stiff sheet metal. The numeral 2 indicates a tapered solid metal stem 70 2, the lower end of which rests upon the small upper end of the conical base 1, and is provided with a depending centrally located lug 3. The numeral 4 indicates a retaining washer which is placed within the 75 conical base 1 and is of such size that it cannot be drawn quite through the small end thereof. The lug 3 is passed through the central perforations of the retaining washer 80 4 and is upset or reversed, to thereby rigidly 85 secure the said base 1 and stem 2 together. The bottom plate 5 of the device is constructed from sheet metal spun or pressed into dish-shaped form and having its out-turned flange coincident with the outer lower edge 90 of the conical base 1, and directly engaging the same. The pliable nonabsorbent facing 6 is fit closely against the bottom surface of the bottom plate 5 and is of approximately 95 the same diameter as the flange thereof. The said parts 1, 5 and 6 are rigidly connected together by a retaining ring 7 having one flange that underlaps the raised edge 100 of the pliable facing 6 and having an upper flange that is overlapped with the lower edge of the conical base 1 and is contracted against the same so as to rigidly connect the 105 said parts.

In Figs. 3 and 4, the numeral 8 indicates a caster socket, the outer and lower contour 105 of which is approximately the same as that of the caster foot above described, and against the lower surface of which the pliable nonabsorbent facing 6^a is applied. In this construction, the pliable facing is held 110 to the socket 8 by a retaining ring 7^a corresponding in shape to the retaining ring 7

and applied in approximately the same way, to-wit, by having its lower flange engaged with the raised upper edge of the facing 6^a and having its upper flange contracted 5 against the upwardly tapered outer surface of the said socket.

The facing 6 and 6^a may be constructed from different materials, but I have obtained the best results by using a heavy cotton fabric, such as cotton belting, and saturating the same with a water proofing material such as paraffin wax. The pliable material thus waterproofed will not absorb moisture and, at the same time, is sufficiently 10 pliable, so that it will not scratch or mar the floor or its finish. The wax produces a very smooth and slippery finish on the pliable facing and therefore make it a very easy 15 matter to move the floor engaging furniture

support, even when the weight of the furniture is thereon. 20

What I claim is:

A furniture foot comprising an approximately hollow conical body, a pan-shaped bottom plate having a raised horizontal marginal flange, a pliable facing applied to and following the form of the bottom of said pan-shaped bottom plate, and a flange retaining ring distinctively independent of the other elements, applied to secure said bottom plate and facing together and to the lower edge of said conical body. 25 30

In testimony whereof I affix my signature in presence of two witnesses.

CHARLIE N. CLARK.
